UNITED STATES PATENT OFFICE.

JOHN H. ASTRUCK, OF NEW YORK, N. Y.

DESIGN FOR A TRAY.

44,121.

Specification for Design.

Patented June 3, 1913.

Application filed March 29, 1913. Serial No. 757,705. Term of patent 7 years.

To all whom it may concern:

Be it known that I, JOHN H. ASTRUCK, a citizen of the United States, residing at New York city, county and State of New York, have invented a new, original, and ornamental Design for Trays, of which the following is a specification, reference being had to the accompanying drawing, forming part thereof.

Figure 1 is a perspective view of a tray showing my new design, and Fig. 2 a plan. I claim:

The ornamental design for a tray, as shown.

JOHN H. ASTRUCK.

Witnesses:

FRANK V. BRIESEN,
KATHERYNE KOCH.
